United States Patent

Des. 236,937
Patented Sept. 30, 1975

236,937

INSULATED BOTTLE WITH ATTACHED CUP

Ronald D. Russo, Colchester, Conn., assignor to
King-Seeley Thermos Co.

Filed Jan. 14, 1974, Ser. No. 433,221

Term of patent 14 years

Int. Cl. D7—07

U.S. Cl. D7—77

FIG. 1 is a side perspective view of an insulated bottle with attached cup showing my new design;

FIG. 2 is a side elevational view thereof, the side opposite being substantially similar;

FIG. 3 is a left end elevational view of FIG. 2;

FIG. 4 is a right end elevational view of FIG. 2;

FIG. 5 is a top plan view thereof; and

FIG. 6 is a bottom plan view thereof.

I claim:

The ornamental design for an insulated bottle with attached cup, substantially as shown and described.
